DALBYS B. KLINETOB, OF MILTON, PENNSYLVANIA

CLAMP AND HOLDING DEVICE WITH HOOK

Application filed September 14, 1931. Serial No. 562,770.

My present invention has reference to a clamp and holding device with hook for connecting the meeting ends of a split neck strap for four-in-hand ties, bow ties, other neck 5 wear; garters and similar and diverse uses where a hook is needed to be clamped to fabrics and similar materials, and for connecting split or severed ends or separate pieces of such fabrics, or wherever a clamp 10 and holding device is needed for such uses.

A further purpose is to strike from a single plate, a device that will, on one end, firmly grip therebetween the ends of the neck strap or other fabric and likewise provide jaws 15 or hooks for interengagement with another like device attached to the other end of the neck strap or other piece of fabric, and when interengaged will provide a means of positively connecting the said ends or pieces, and 20 by the special formation of the jaws or hooks the free movement between the fasteners is absolutely prevented. While each device is separate and individually alike, yet any two will unite or interengage and thus provide a 25 pair for the fulfillment of the above mentioned ideas.

A further object is to construct a fastener or clamp and holding device with a jaw or hook for this purpose of a single plate of 30 metal.

Besides other uses, said clamp and holding device is to be an attachable accessory to a four-in-hand neck tie or any neck band of a similar type, and or wherever a detachable 35 band would be advantageous.

To the attainment of the foregoing and other objects which will present themselves as the nature of the invention is better understood the invention consists in the improvement 40 hereinafter described and definitely claimed.

In the drawing:

Figure 1 is a perspective view showing the neck strap of a four-in-hand tie having its 45 ends fastened in accordance with this invention.

Figure 2 is a plan view of the blank from which the fastener is formed.

Figures 3 and 4 are side elevations illustrating the fasteners separated.

Figure 5 is a perspective view thereof.

Figure 6 is a longitudinal sectional view through the interengaging fasteners.

Figure 7 is a perspective view of one of the fasteners prior to the bending of the integral 55 clamping plate against the body of the fastener.

Figure 8 is an end view to better illustrate the interengagement of the teeth between the body of the fastener and the clamp plate of 60 the fastener.

I am aware that there are a number of devices for fastening the meeting ends of split neck bands of four-in-hand or bow ties but in the main such fasteners are adjustably connected to the neck straps, are not easily fastened together and are of a complicated nature. While the fastener that forms the subject matter of this application is adaptable to the split neck straps of any class of neckties, the same is primarily designed for use in connection with four-in-hand ties of the ordinary construction, which after the same is properly knotted has its neck portion 1 cut transversely, and to the ends of the neck band 70 or strap the fasteners are attached. By this arrangement a perfectly hand knotted tie 75 may be easily and quickly arranged beneath the folds of a collar so that the knotting of the tie, each time it is worn, is thus effectively overcome.

The fasteners as disclosed by Figure 2 are each struck from a single plate of thin, strong but bendable metal. This plate 2 has one of its edges formed with a projection 3, 85 and at a distance inward from the projection the plate is slotted longitudinally, as at 4, and is likewise slotted for a determined distance, as at 5. The ends of the extension 3 are slightly beveled, and it is to be noted that the slits 5 are disposed approximately in a line with the ends of the said extension 3. The metal bounded by the slits 4 and 5 is indicated by the numeral 6, and this part 6 is designed to be bent upon a longitudinal fold 90 line 7 to overly the body plate 2. Prior to the bending of the part 6 the same, adjacent to its outer edge, is punched from one of its faces to provide the same with tapered but saw-tooth shaped prongs 8. The body plate, 100

adjacent to the straight edge thereof, is likewise punched in the same direction from the punched portion 6 and by thus punching the body plate the same is afforded with conical 6 projections that are formed with saw-shaped teeth or prongs 9, and the teeth or prongs 9 are so arranged that the spaces therebetween are disposed in a plane or directly opposite the saw teeth 8 and the conical projections of 10 the part 6, when the said part 6 is bent upon a score line over the body plate 2.

The body plate, inward of the end thereof provided with the extension 3 is bent upon a score line 10 against the face of the body plate 15 opposite that over which the part 6 has been bent. The plate is rounded upon itself at its last-named bent portion and the said bent portion provides the plate with a jaw 11 that is arranged parallel with but is spaced from 20 the body plate and the extension 3 on the jaw 11 provides the said jaw with a lip. For distinction the space or opening between the jaw 11 and the body plate afforded by the slotted portions 4 and 5 is indicated by the numeral 25 12.

One of the slit ends of the neck strap 1 of the tie is passed over the body plate and the overlying part 6 is forcibly pressed against the body plate. The conical teats 30 provided with the teeth 8 and 9 will have their said teeth brought to impinging engagement with the end of the strap 1. Because the teeth 8 are received in the spaces provided by the teeth 9 the end of the tie will be effectively 35 secured to the fastener. The second end of the tie has the cooperating fastener attached thereto in the same manner as just described and the jaws of the respective fasteners are passed through the spaces 12 to bring the said 40 jaws over each other as clearly disclosed by Figure 6 of the drawings. The lips 3 on the jaws are now positioned to slightly contact with the confronting walls 13 provided by the projecting arms 14 that afford the space 12. 45 The coengaging fasteners may be easily and quickly brought into engagement with each other and the lips 3 on the jaws of the said fasteners will prevent the same from moving longitudinally through the space or 50 opening 12 in the respective fasteners, and it is thought that the foregoing description will fully and clearly set forth my construction and its advantages without further detailed 55 description.

55 Obviously I do not wish to be restricted to the precise details herein set forth and, therefore, hold myself entitled to make such changes therefrom as fairly fall within the scope of what I claim.

60 Having described the invention, I claim:
1. Cooperating fasteners for the split ends of the neck strap of a neck tie or the like, each formed from a metal plate shaped to provide an overlying part that is bendable against 65 the body of the plate when an end of the strap

is received therebetween, interengaging impinging elements on the plate and said overlying part, and the outer ends of the plates being formed with jaws designed for interengagement and with openings through 70 which the jaws pass.

2. Cooperating fasteners for the split ends of the neck strap of a neck tie or the like, each formed from a metal plate shaped to provide an overlying part that is bendable against the body of the plate when an end of the strap is received therebetween, interengaging impinging elements on the plate and said overlying part, and the outer ends of the plates being formed with jaws designed for interengagement and with openings through 75 which the jaws pass and each of said jaws having a lip extension arranged slightly out of contact with the confronting walls provided by the openings. 80

3. Fasteners for the confronting ends of a split neck strap for a necktie or the like, each comprising a flat plate which has one of its ends punched to provide conical teats having saw teeth and its second end formed with an extension, said plate, inward of the extension being slotted longitudinally and transversely and the part bounded by the slit being punched at the slotted end thereof to provide conical projections which are provided with saw teeth, said part being bent on the body plate to provide an overlying part which is adapted to be forced against the plate when an end of the neck band is received on said plate to cause the saw teeth of 90 the conical teats to pierce said strap, the body plate, outward of the overlying part thereon being bent upon itself to provide an underlying jaw, and a lip extending from said jaw. 95

4. Fasteners for the purpose set forth, each comprising a plate having a bendable part formed therewith, coengaging impinging elements on said part and the plate, and each of said plates having a hooked end designed for coengagement. 105

5. Fasteners for the purpose set forth, each comprising a plate having an integrally formed overlying bendable part, coengaging impinging elements on said part and plate, each of said plates having a jaw end designed 115 for coengagement, and said plates being also provided with openings for the passage of the respective jaws and with whose end walls the jaws are designed to contact. 120

6. Fasteners for the purpose set forth, each comprising a substantially rectangular plate, cut and provided with a bendable part that is arranged over the body of the plate, co-operating impinging elements on the overlying part and plate, said plate having its end outward of the said cut-away portion formed with a lip, and the said end being bent under the plate to provide a jaw, the jaws of the respective plates designed for coengagement. 125

7. Fasteners for the purpose set forth, each comprising a substantially rectangular plate, integrally formed with a yieldable part that overlies the body of the plate, cooperating 5 impinging elements on said part and plate, said plate having one of its ends formed with a jaw, and the jaws on the respective plates adaptable for coengagement.

In testimony whereof I affix my signature.
